UNITED STATES PATENT OFFICE.

JOSEPH WESOLIK, OF BELLEVILLE, ILLINOIS, ASSIGNOR OF ONE-FOURTH TO EWALL LUETSCHER, OF BELLEVILLE, ILLINOIS, AND ONE-HALF TO LUDWIG KIBBEN, OF CLINTON, MASSACHUSETTS.

RAIL-FASTENING PLATE.

Application filed September 11, 1922. Serial No. 587,363.

To all whom it may concern:

Be it known that I, JOSEPH WESOLIK, a citizen of the United States, residing at Belleville, in the county of St. Clair and State of Illinois, have invented certain new and useful Improvements in Rail-Fastening Plates, of which the following is a specification.

My invention relates to rail fastening plates, and is a distinct and practical improvement to overcome certain practical objections to, and defects in, the present method of holding rails upon ties by means of spikes.

The object of my invention is to provide a rail fastening plate having yieldable means to be brought into embracing engagement with the base flanges of the rails by means of screw-threaded elements, which elements also serve the dual function of preventing lateral displacement, or spreading of the rails, when threaded into the ties.

A further object of the invention is to provide a rail fastening plate which will serve at the joint of two rails and aid in holding the rails in alignment.

With the above and other objects in view, as will appear hereinafter, the detail construction entering into my invention will be hereinafter fully described and finally pointed out in the claims hereto appended.

Referring to the accompanying drawings forming a part of this specification, wherein like characters of reference denote similar parts throughout the several views:

Fig. 1, is a perspective view of a rail fastening plate embodying the features of my invention.

Fig. 2, is a side elevation thereof together with a cross section of a rail positioned thereon but not as yet fastened thereto.

Fig. 3, is a view similar to Fig. 2, showing the rail fastened to the plate and the plate secured to the tie.

Fig. 4, is a plan view of the invention as it appears applied to a rail and tie.

Fig. 5, is a perspective view of the rail fastening plate as used at the joint of two rails.

Fig. 6, is a plan view of Fig. 5.

Referring to the drawings, the reference character 1 represents a wooden tie while 2 represent a rail.

In carrying out the aim of my present in-

vention, I employ a metallic plate 3 preferably of steel and which is preferably rectangular in shape. The corners of the plate 3 are bent downwardly to form prongs 4 which serve as anchors for the plate when embedded into the tie 1 to aid against displacement of the plate when positioned upon the tie 1.

Punched from the plate 3 and disposed opposite one another are a pair of rail embracing lips 5 and 6. Each of these lips is provided with an inclined or angular body portion 7 which is integral with the plate 3 and which terminates in a horizontally disposed portion 8 provided with an opening 9. The lips 5 and 6 are directed toward each other but are spaced a sufficient distance apart to provide a gap of somewhat less width than the base flanges 10 of the rail 2, as is evident from Fig. 1, of the drawings.

The body portion 7 of lip 5 is directed at a greater acute angle than angularly disposed body portion of lip 6 so as to provide a greater gap between the body portion 8 of lip 5 and the plate 3 than between the body portion 8 of lip 6 and plate 3 so as to permit one of base flanges 10 of the rail 2 to be first inserted into the gap between the lip 5 and base 3, as shown in dotted line A in Fig. 2, and then moved laterally until the other base flange enters the gap between lip 6 and the base 3, as clearly illustrated in Fig. 2. When the rail is in normal position, the edges of the base flanges lie in alignment with the inner curve of the openings 9, as clearly shown in Fig. 2.

After the rail has been positioned upon the fastening plate 3, a suitable lag screw 11 is receivable in each of the openings 9 of the embracing lips 5 and 6 and forced into the tie causing the heads 12 of the screws 11 to draw the lip portions 8 of the embracing lips 5 and 6 into contact with the upper face of the base flanges 10 of the rail 2, as clearly shown in Fig. 3. It will be observed that the shank or stem of the screws engages the side edges of the rail flange to prevent any possible spreading or displacement of the rails after the screws have been brought home.

It will be apparent from the drawings that the lip portions 8 of the lips 5 and 6 embrace the base flanges of the rails and

serve the same function as the heads of the spikes now used for anchoring rails to the ties.

The lips 5 and 6 being resilient or yieldable under pressure always enables the gap between the lips 5 and 6 and the fastening plate 3 to be increased whenever the screws 11 are removed from the ties, thus permitting easy removal of the rails from the fastening plates, or vice-versa during repair work, owing to lips returning to their normal position after the screw pressure has been released.

When the fastening plates are employed at the joint between two adjacent rails, the width of the lips 5 and 6 is increased to double the width of the lips shown in Fig. 1 or greater and each lip is provided with two bolt openings 9 instead of one. This increased width of the lips 5 and 6 permits embracing therein the flanges of both rails and the double screw arrangement positively holds the two rails at their ends in alignment.

It is possible with rail fastening plates as herein described to eliminate a large number of ties to the mile, and, this is especially true in mine track construction, as there is no possible chance for the spreading or displacement of the rails, as the plates and screws must first be displaced upon the ties which is impossible, wherein with the use of spikes alone for holding the rails upon the ties, it is possible for rails to spread or be displaced whenever the spike becomes the least bit loose in the tie due to vibrations caused by rolling stock.

It is evident that the ties can be provided with openings 13 for the reception of the lag screws 11, said openings, of course, being less in diameter than the screws 11 so they will not fit loose therein when brought home. Ties provided with the openings 13 permit the track layers to quickly position the rail fastening plates upon the ties by simply registering the openings 9 of the embracing lips 5 and 6 with the openings 13 in the ties.

It is apparent from the foregoing description that I provide a rail fastening plate that is simple in construction, easily and quickly applied to or removed from the rails and highly efficient for the purpose intended, namely, the elimination of spikes for rail fastening purposes.

The many advantages of the herein described invention will readily suggest themselves to those skilled in the art to which it appertains.

I do not wish to be understood as having limited myself to the exact details of construction shown and described, but desire to have it understood that the invention I have shown in the drawings is merely illustrative, as it is manifest that various minor changes may be made in the form, shape

and particular arrangement of parts without departing from the spirit of my invention, hence I reserve the right to make any such changes, or modifications as may fairly fall within the scope of the appended claims 70 when fairly construed.

What I claim is:

1. The combination with a flanged rail and a wooden tie, of a clamping plate adapted to be seated upon the tie, opposed rail 75 flange embracing members directed upwardly and inwardly from said plate and headed locking members extending through the rail flange embracing members for clamping the plate to the rail so that the 80 embracing members thereof will be sprung to apply yielding pressure to the rail flange and said locking members engaging the edges of the rail flange to prevent displacement thereof upon the plate. 85

2. The combination with a flanged rail and a wooden tie, of a clamping plate adapted to be seated upon the tie, said plate having opposed yieldable embracing lips with their free edges lying over the flange of the rail 90 and a headed locking member for each lip serving the double purpose of preventing the plate from displacement upon the tie and clamping the lips so that they spring or bend to apply yielding pressure to the flanges of 95 the rail.

3. The combination with a flanged rail and a wooden tie having an opening adjacent each base flange of the rail, of a clamping plate of steel having its corners turned down 100 to serve as anchors when driven into the tie, a pair of opposed embracing lips stamped from said plate each having an opening adapted to register with the openings in the tie, said lips overlying the base flange of the rail and headed locking means passing through the openings of the embracing lips and into the openings of the tie for applying yielding pressure of the embracing lips 110 to the rail flange and engaging the edges of the rail flange to prevent displacement of the rail. 105

4. The combination with a pair of flanged rails arranged end to end and a wooden tie support therefor, of a rail fastening plate 115 having clamping means for embracing the base flanges of the rails and locking means to apply yielding pressure of the embracing lips to the rail flanges and to engage the edges of the rail flanges to prevent displacement of the rails from their aligned position. 120

5. A rail fastening plate comprising a rectangular metallic plate, a pair of opposed yieldable rail flange embracing lips each having a screw receiving opening, said lips being punched from the plate and so shaped as to provide a rail flange receiving space between the embracing lips and the upper plane of the plate. 125 130

6. A rail fastening plate comprising a rectangular metallic plate, anchoring means formed at the corners of the plate, a pair of opposed yieldable rail flange embracing lips each having a screw receiving opening, said lips being punched from the plate and so shaped as to provide a rail flange receiving space between the embracing lips and the upper plane of the plate.
- 10 7. A rail fastening plate comprising a rectangular metallic plate, a pair of opposed yieldable rail flange embracing lips each having a screw receiving opening, said lips being punched from the plate and so shaped as to provide a rail flange receiving space between the embracing lips and the upper plane of the plate, one of said embracing lips
- being so bent as to provide a deeper flange receiving space than the opposite lip.
8. A rail fastening plate comprising a rectangular metallic plate, anchoring means formed at the corners of the plate, a pair of opposed yieldable rail flange embracing lips each having a screw receiving opening, said lips being punched from the plate and so shaped as to provide a rail flange receiving space between the embracing lips and the upper plane of the plate, one of said embracing lips being so bent as to provide a deeper flange receiving space than the opposite lip.
- 15 In testimony whereof, I have hereunto signed my name to the specification.

JOSEPH WESOLIK.
